TOOTH FOR A POWER DIGGER

Gerald D. Edwards, 207 SW. Murphy, Burleson, Tex.
76028, and Floyd B. Edwards, Rte. 3, Box 245, Canton,
N.C. 28716

Filed Aug. 30, 1968, Ser. No. 13,334

Term of patent 14 years

Int. Cl. D15—03, 04

U.S. Cl. D39—1

FIGURE 1 is a perspective view of the tooth, a bracket or adapter on which the tooth may be mounted being shown in dot-dash lines for illustrative purposes only;
 FIGURE 2 is a side view of the tooth;
 FIGURE 3 is a front view of the tooth;
 FIGURE 4 is a top view of the tooth; and
 FIGURE 5 is a rear view of the tooth.

We claim:

The ornamental design for a tooth for power digger, as shown and described.
